ABSTRACT OF THE DISCLOSURE

A motor driven tire carried on a frame supported on the catwalk board above the bowling ball return track, the tire traction surface extending downward to normally engage the upper surface of the bowling ball as the latter returns along the track from the pit end to the head end of the alley to accelerate the return speed. Combination hold down and jacking means selectively lock the frame down to the catwalk board for ball driving engagement or elevate the frame to prevent engagement of the tire with the bowling balls, and leveling means adjust the degree of engagement between the tire and ball.

This invention relates generally to bowling ball fast return mechanisms associated with the ball return runway of a bowling alley and operative to rapidly return a bowling ball from the pit end of the bowling alley to the head end of the alley, the return mechanism being usable with either manual return alleys or with automatic pin setting machine.

Bowling ball fast return mechanisms are not per se new, but such known devices are generally incorporated into a ball return system in such manner that in the event of a breakdown or jamming of the bowling ball fast return device the return runway is rendered inoperative and the alley or alleys served by it must be taken out of service until a repairman is available to repair the breakdown. The fast ball return system according to the present invention is not so limited, in that, while itself being a very simple device not normally subject to breakdown or jamming, nevertheless, in the event that such should occur, the mechanism is so constructed that it may be immediately shifted from the path of ball return so as to occupy a non-engaging position as regards a bowling ball returning along the trackway. Consequently, no bowling alley need be taken out of service because of any malfunction in the fast return system.

It is therefore a primary object of this invention to provide a novel bowling ball fast return device of simple mechanical configuration which may quickly and easily be installed into existing bowling ball return runway equipment in such manner that it may readily be adjusted to a position of non-engagement with a returning bowling ball in the event of a malfunction of the fast return device and thereby completely eliminate out-of-service time for any bowling alley with which it is used.

Another object of this invention to provide a novel bowling ball return device as aforesaid which includes means for adjusting the degree of engagement between a bowling ball and the fast return mechanism to provide an effective range of control over the return speed of the bowling ball.

2

A further object of this invention is to provide a novel bowling ball return device as aforesaid which includes a leveling mechanism operative to insure that the fast ball return device engages the bowling ball at the right point on the periphery of the latter.

5 The foregoing and other objects of the invention will become clear from a reading of the following specification in conjunction with an examination of the appended drawings, wherein:

10 FIG. 1 is a perspective view of the fast ball return device shown associated with a portion of the ball return runway of a bowling alley;

15 FIG. 2 is a side elevational view of the apparatus according to the invention illustrating a bowling ball in operative engagement with the ball return mechanism;

20 FIG. 3 is a horizontal sectional view through the cover of the apparatus according to the invention looking down at the interior mechanism as would be seen when viewed along the line 3—3 of FIG. 2;

25 FIG. 4 is an end elevational view of the apparatus as would be seen when viewed along the line 4—4 of FIG. 2, with a superimposed phantom showing of the apparatus when in elevated position for non-engagement with the bowling ball;

30 FIG. 5 is a side elevational view similar to that shown in FIG. 2 excepting that the apparatus is seen in disengaged position corresponding to the phantom showing of FIG. 4;

35 FIG. 6 is a view of the apparatus as would be seen in end elevation when viewed from the head end of the alley; and

40 FIG. 7 is an exploded perspective view of some of the parts of the apparatus according to the invention with the bowling ball driving components removed.

45 In the several figures, like elements are denoted by like reference characters.

Referring now to the drawings, the bowling ball fast return device is designated generally as 10 and includes a frame 11 to which are mounted the operative parts of the return mechanism and a cover 12. The frame 11 is in the form of a U-shaped member having side legs 13 connected together at one end by a bridging leg 14 from which project a pair of studs 15, the bridging leg 14 being pivotally connected by means of a hinge 16 to a catwalk board 17 which overlies a portion of the return track 18 at the pin pit end of the alley. The catwalk board 17 is cradled proximate to its opposite ends by a pair of saddle brackets 19 each having outwardly turned slotted upper ears 20 supported in vertically adjusted positions by nuts 21 on vertically extending threaded studs 22 which latter are rigidly secured to support posts 23.

50 Affixed to the frame side legs 13 near the free swinging end are a pair of pillow blocks 24 within which is journalled for rotation a shaft 25 having mounted thereupon a deformable tire 26, one end of the shaft 25 having fixedly secured thereto for rotation therewith a pulley 27 about which is trained a drive belt 28 which is also trained about a second pulley 29 fixed upon the shaft 30 of an electric motor 31. The electric motor 31 is journalled in a support bracket 32 which is eccentrically connected to a pivot bar 33 journalled for swinging movement in supports 34 which latter are fixedly secured to the side

legs 13 of the frame 11. The off center location of the motor 31 with respect to its pivot bar 33 maintains tension on the drive belt 28. The catwalk board 17 is suitably cut out at 35 and 36 to allow free clearance for the tire 26 and the pulley 27. A junction box 37 secured to the frame 11 adjacent to the bridging leg 14 provides a source of electric power for the motor 31 from an electric supply line 38 and an electric control line 39 connected to any suitable means for controlling energization and deenergization of the motor 31.

The free ends of the side legs 13 of the frame 11 are fixedly secured to a rigid plate 40, as for example by welding, and an ear 41 is turned-up out of the body of the plate 40 to provide a bolting securement for the cover 12. The wall 42 of the cover 12 is apertured proximate the bottom corners as at 43 to receive therethrough the studs 15 extending from the bridging leg 14, while the opposite end wall 44 of cover 12 is provided with a bolt hole 45 through which is projected a securing bolt 46 threaded into the ear 41 of the plate 40 to thereby lock the cover to the frame 11. The cover 12 is of course removable by merely unscrewing the bolt 46 and pivoting the cover up and disengaging the frame studs 15 from the cover apertures 43.

From the showing of FIG. 7 it is clear that the frame 11 and all of the driving apparatus carried thereby is only secured to the catwalk board by the hinge 16, and if not secured at the other end in some manner would tend to bounce when the tire 26 were engaged by a bowling ball 47, as for example shown in FIGS. 2 and 4. The operation of the ball return device would be at best erratic and certainly unreliable. This problem is overcome by means of a combination hold down and jack device which acts in conjunction with the rigid plate 40 to lock the frame 11 to the catwalk board 17 as shown for example in FIGS. 1, 2 and 3, while providing the function of a jacking device as shown in FIG. 5 to raise the frame 11 and the driving mechanism to a point where the tire 26 cannot engage a bowling ball riding thereunder down the return track toward the head end of the alley. This jacking feature is of course very important in the event of an electrical or mechanical breakdown of the ball return mechanism 10 because it provides the means for quickly effectively removing the return device 10 from operative engagement with the bowling ball so that the normal gravity return system may still be operative to thereby keep the alleys in service until such time as the return device can receive the attention of a repairman.

The combination hold down and jacking device includes a threaded stud 48 extending vertically with its shank projecting upward through the catwalk board and secured to the board by means of a washer 48 and nut 50. Seated flatwise upon the upper surface of the nut 50 by projection of the stud shank through a hole punched therethrough is the locking-jacking plate 51 having a turned down locking edge 52 at one end and a turned up jacking edge 53 at the opposite end. Threaded down onto the shank of the stud 48 in overlying clamping relationship to the locking-jacking plate 51 is a wing nut 54. Since the plate 51 is freely swingable about the stud shank when the wing nut 54 is released, it is clear that either the locking edge 52 or the jacking edge 53 may be placed in operative position with respect to the rigid plate 40 affixed to the frame 11.

With the locking edge 52 overlying the plate 40 and the wing nut 54 threaded down tightly onto the shank of the stud 48, the plate 51 locks the frame 11 to the catwalk board 17 so that the tire 26 may be operatively engaged with the bowling ball as the latter moves down the return track 18. Should it become desirable to remove the return device 10 from operative service it is only necessary to release the wing nut 54, turn the locking-jacking plate 51 through about ninety degrees to clear the locking edge 52 from above the plate 40, lift the return device 10 and swing the locking-jacking plate 51

through an additional ninety degrees to bring the jacking edge 53 beneath the plate 40, and finally, retighten the wing nut 54.

The cover 12 is of course attachable and removable from the frame 11 regardless of whether the return device 10 is in its locked down or elevated position. Finally, the degree of engagement between the driving tire 26 and the bowling ball 47 is completely controllable by adjustment of the elevation of the saddle brackets 19 on the threaded studs 22.

Having now described my invention in connection with a particularly illustrated embodiment thereof, it will be appreciated that modifications and variations of my invention may now occur from time to time to those persons normally skilled in the art without departing from the essential scope or spirit of my invention, and accordingly, it is intended to claim the same broadly as well as specifically as indicated by the appended claims.

What is claimed to be new and useful:

1. A bowling ball fast return device comprising in combination,

(a) a catwalk board suspended above the bowling ball return track at the pit end of the bowling alley, a frame secured to and supported on said catwalk board, a motor driven tire carried on said frame said tire having a traction surface extending downward to normally engage a portion of the upper surface of a bowling ball as the latter returns along the track from the pit end to the head end of the alley to accelerate the return speed of the ball,

(b) combination hold-down and jacking means selectively operable respectively to lock the said frame down to the catwalk board for ball driving engagement and to maintain the said tire elevated to a height sufficient to prevent engagement of said tire with bowling balls passing therebeneath, and

(c) leveling means supporting said catwalk board operative to adjust the degree of engagement between said tire and a bowling ball.

2. A bowling ball fast return device as set forth in claim 1 wherein said frame is hingedly secured at one end to said catwalk board and wherein said hold-down and jacking means is anchored to said catwalk board proximate to one side of said frame which is opposite the hinged securement of said frame to said catwalk board, said hold-down means being shiftable into overlying relation to said frame one side and clampable downward thereon to effect locking of the frame to the board, said hold down means being releasable and shiftable to clear away from said frame one side whereby to permit elevation of said frame from said catwalk board about the hinged securement, and said jacking means being shiftable under said frame to support the latter in its elevated position.

3. A bowling ball fast return device installable above the return track of a bowling alley for accelerating the return of a bowling ball from the pit and to the head end of the bowling alley, comprising in combination,

(a) a ball drive member having a drive surface engageable with a portion of the upper surface of a bowling ball,

(b) selectively operable power means coupled to said ball drive member effective when operated to move the said drive surface in the same direction as and at a speed substantially higher than the normal surface speed of a bowling ball moving along the return track toward the head end of the bowling alley,

(c) selectively operable means operatively coupled to said ball drive member effective to adjust the degree of surface engagement between said ball drive member and a bowling ball moving along the return track and to effect correct orientation of the axis of rotation of said ball drive member in relation to the axis of rotation of said bowling ball, said last mentioned means including

- (1) a supporting platform for said ball drive member and power means spaced vertically above said return track and having a slot therein through which said ball drive member downwardly projects for engagement with a bowling ball moving along said track,
 5
 (2) vertically extending jack screw means disposed in longitudinally spaced relation along-side opposite sides of said platform adjacent the fore and aft ends thereof, and
 (3) means for adjusting the elevation of said platform relatively to said track at each of the points of securement of said platform to said jack screw means for leveling said platform and so present-

ing said ball drive member in correctly oriented position relatively to the bowling ball engaged thereby, said last-mentioned means being further operative to completely release said ball drive member from driving engagement with said bowling ball.
